CURTAIN ACCESSORY

George F. Heubeck, Baltimore, Md.

Application March 17, 1947, Serial No. 735,074

4 Claims. (Cl. 160—349)

1

An accessory embodying the invention is particularly adapted for use with a bathtub shower curtain and it is so shown and described. It will be understood, however, that the invention is not necessarily so limited.

In the use of a bathtub shower curtain, water or spray from the shower ordinarily escapes, sometimes in considerable quantities, through the spaces between the edges of the curtain and the adjacent walls of the room. This is obviously objectionable and the principal object of the present invention is to provide a simple and inexpensive accessory or device which can be associated with the curtain and its supporting rod and which will serve to hold one edge of the curtain close to or against the adjacent wall so that water cannot escape. Ordinarily two devices are used at the respective edges of the curtain.

An accessory or device incorporating the present invention includes a member adapted to be clamped to the curtain rod and also includes a bar extending downward from the said member and adapted to releasably hold the corresponding edge of the curtain. Preferably the device can be manually released from its clamping engagement with the curtain rod and can be moved along the rod carrying a portion of the curtain with it, thus opening the curtain for entrance or egress of the user.

In the drawings I have shown in detail three embodiments of the invention, but it will be understood that various changes may be made from the constructions shown, and that the drawings are not to be construed as defining or limiting the scope of the invention, the claims forming a part of this specification being relied upon for that purpose.

Of the drawings:

Fig. 1 is a side view showing a bathtub, a shower curtain, together with the supporting rod therefor, and an accessory or device incorporating the present invention.

Fig. 2 is an end view of the parts shown in Fig. 1.

Fig. 3 is an enlarged front view of the device as shown in Fig. 2, together with a portion of the curtain, a portion of the supporting rod and a portion of the adjacent wall.

Fig. 4 is a side view of the device as shown in Fig. 3.

Fig. 5 is a plan view of the device as shown in Fig. 3.

Figs. 6, 7 and 8 are views similar respectively to Figs. 3, 4 and 5, but showing an alternative embodiment of the invention.

2

Figs. 9, 10 and 11 are views similar respectively to Figs. 3, 4 and 5, but showing another alternative embodiment of the invention.

Referring to the drawings, particularly Figs. 5 and 2 thereof, 10 represents a bathtub which is shown as located in the corner of a room in contact with the vertical walls 12 and 14. Secured to the walls 12 and 14 is a horizontal L-shaped curtain supporting rod 16. The shower curtain is shown at 18, this being provided with a plurality of uniformly spaced hooks or rings 20, 20 which engage the rod 16.

The accessory or device to which the invention more particularly relates is indicated generally at 22. Two devices are provided near the respective ends of the rod 16 and adjacent the respective walls 12 and 14. The two devices may be identical in construction, but they are mounted on the rod in relatively reversed positions.

As shown in detail in Figs. 3, 4 and 5, each device comprises a member 24 at the top which is engageable with and supported by the curtain rod 16. A means generally indicated at 26 is provided for clamping the member 24 on the rod to hold it in fixed relation thereto. Depending from the member 24 is a generally vertical bar 28 which is immediately adjacent the corresponding wall, as for instance the wall 14. The bar 28 is adapted to releasably engage an edge portion of the curtain to hold it against movement relatively to the bar. The resiliency of the bar is such that the curtain is thus firmly gripped and held throughout a substantial portion of the length of the bar. The bar 28 is provided adjacent its lower end with means for more firmly engaging the edge portion of the curtain. The last said means may be varied, but preferably and as shown, it comprises knurling 30 on the bar, the said knurling tending to prevent any slippage of the curtain. The bar 28 is shown at the outer side of the curtain and the edge of the curtain extends outward between the bar and the wall. However, the bar may be at the inner side of the curtain and in that case the curtain would extend inward between the bar and the wall. While the bar 28 may be at the outer side of the curtain as shown, the clamping means is at the inner side of the curtain so as to be conveniently accessible.

As shown in Figs. 2 and 3, each device 22 is preferably mounted between two of the curtain rings 20, 20. When the clamping means 26 is released the member 24, and in fact the entire device, may be moved along the rod carrying the

edge portion of the curtain with it. This enables the curtain to be opened to permit convenient entrance or egress of the user.

While the bar 28 is generally vertical, as already stated, it is preferably provided with an offset 31 which serves to position the main portion of the bar directly below the center of the rod 16. The bar 28 is also preferably provided with an offset 32 which enables the upper portion thereof to readily clear a ledge 33 such as is commonly provided in tiled bathrooms. When the offset is provided, the upper portion of the bar readily clears the ledge, but the lower portion thereof is closely adjacent the main surface of the vertical wall so as to be adapted to engage the edge portion of the curtain as already stated.

The device may be varied widely as to details, but preferably and as shown, the bar 28 and the rod engaging member 24 are formed integrally. The upper portion of the bar is bent to form a loop 34 in which the rod 16 is received. From the lower end of the loop 34 there extends a generally longitudinal portion 36 which joins a second loop 38 in which the rod 16 is also received. Beyond the loop 38 there is another longitudinally extending portion 40. The longitudinally extending portions 36 and 40 are shaped to provide upward opening recesses in which a portion of the clamping means is seated.

The clamping means is shown as comprising an element 42 having trunnions at the end which are seated in the recesses in the said longitudinal portions 36 and 40. The element 42 has a threaded aperture therein through which extends a vertical screw 44. The screw 44 is shaped at its lower end to provide a handle 46 by means of which it can be readily turned manually. Supported on the upper end of the screw 44 is a shoe 48 which is shaped to engage the bottom of the rod 16. It will be understood that the screw 44 is rotatable relatively to the shoe 48. It will be seen that when the screw 44 is turned by means of the handle 46, the shoe 48 is pressed upward against the bottom of the rod 16 to effect clamping.

Preferably the top of the loop 34 which is nearer the wall is slightly lower than the top of the other loop 38. Thus when the parts are in the positions shown in Fig. 3, the top of the loop 38 is out of engagement with the rod. When clamping pressure is applied the member 24 is tilted in the counterclockwise direction, with the top of the loop 34 acting as a fulcrum. This tilting serves to more firmly press the lower end of the bar 28 against the curtain 19. The pivotal connection of the clamping means to the member 24 facilitates the tilting action.

With the curtain open the member 24 is loosely supported on the rod 16. When it is desired to close the curtain the device is moved toward its adjacent wall until the bar 28 comes into position for contact with the wall, the curtain being moved with the device. Ordinarily the edge portion of the curtain is automatically caught and held between the rod and the wall, and then the screw 44 is turned to lightly clamp the device in place on the rod. If the edge portion of the curtain is not fully engaged automatically, it may be manually adjusted so as to be satisfactorily held. The knurling 30 serves to provide additional resistance at the bottom to relative movement of the curtain. If more secure holding of the curtain is desirable after any necessary manual adjustment thereof, this may be obtained by

further tightening the clamping device so as to tilt the member 24 as already described and press the lower end of the bar more firmly against the curtain. When the curtain is to be opened it is merely necessary to release the clamping means and to move the device away from the wall carrying the curtain with it.

The device as shown in Figs. 6 to 8 is in many respects similar in construction and in function to that shown in Figs. 3 to 5, and repetition of the detailed description is unnecessary. The parts 28, 31, 32, 34 and 38 are or may be the same as the similarly numbered parts as shown in Figs. 3 to 5.

15 The lower portion of the bar 28 as shown in Figs. 6 to 8, in addition to being provided with a knurled end 30, is provided with a pin 52 which extends beyond the ring and is pointed to engage the curtain and more firmly hold it.

20 In lieu of the longitudinal portions 36 and 40, as shown in Figs. 3 to 5, somewhat different longitudinal portions 54 and 56 are provided which are shaped to provide semi-circular upward opening recesses. Seated in the recesses in the longitudinal portions 54 and 56 are centrally apertured grooved discs 58 and 60. Positioned between the discs 58 and 60 is an element 62 which is shaped to fit the bottom of the rod 16 and which is provided with trunnions 64 and 66 extending through the apertures in the discs 58 and 60. The element 62 is eccentrically mounted with respect to its trunnions, as indicated in Fig. 6, and it carries a lever 70 by means of which it may be turned about the axis of the trunnions. 25 Fig. 6 shows the lever 70 vertical with the element 62 in clamping engagement with the rod 16. When the lever 70 is swung toward the left, the element 62 is rotated sufficiently to disengage the bar 16, thus permitting free movement of the device along the rod.

30 It will be observed that Fig. 6 shows the bar 28 at the inner side of the curtain instead of at the outer side thereof. As already stated, it is optional whether the bar be at the inner side of the curtain or at the outer side.

35 The device as shown in Figs. 9 to 11 is also in many respects similar in construction and in function to that shown in Figs. 3 to 5 and repetition of the detailed description is unnecessary. The parts 28, 30, 31, 32, 34 and 38 are or may be the same as the similarly numbered parts as shown in Figs. 3 to 5.

40 The knurling 30 at the lower end of the bar 28 may be provided with a pointed pin 52 similar in function to the pointed pin 52 shown in Figs. 6 to 8. This serves to engage the curtain and more firmly hold it.

45 In lieu of the longitudinal portions 36 and 40 as shown in Figs. 3 to 5, somewhat different longitudinal portions 74 and 76 are provided which are straight. Resting on the longitudinal portions 74 and 76 is an element 78 having a threaded aperture therein. A vertical screw 80 extends through the aperture in the element 78 and carries at its upper end a shoe 82 shaped to engage the bottom of the rod 16. It will be understood that the screw 80 is rotatable relatively to the shoe 82. The screw 80 has a knurled enlargement or head 84 by which it may be manually turned. It will be seen that when the screw 80 is turned the shoe 82 is forced upward against the rod 16 to effect clamping in the manner already described.

50 I have described the device in connection with a shower curtain for which it is particularly

adapted. However, it will be understood that the device is not necessarily limited for use with a shower curtain and may be used with any curtain which is supported on a rod.

What I claim is:

1. A device for use in conjunction with a curtain, a horizontal supporting rod therefor and a vertical wall adjacent one end of the rod, the said device comprising in combination a member having a portion engageable with the top of the curtain rod adjacent the wall, a resilient bar rigidly connected with the curtain rod engaging member and extending downward therefrom, the said bar being adapted for engaging an edge portion of the curtain to press it against the wall and thus hold it against movement relatively to the bar, and clamping means carried by the curtain rod engaging member and engageable with the bottom of the rod to hold the said member in fixed relation to the rod, the last said means tending to tilt the member downward about the said rod engaging portion and thereby tending to swing the downward extending bar toward the wall to more firmly engage the curtain.

2. A device for use in conjunction with a curtain, a horizontal supporting rod therefor and a vertical wall adjacent one end of the rod, the said device comprising in combination a member engageable with the curtain rod adjacent the wall, the said member having at the top two longitudinally spaced rod engaging portions with the portion nearer the wall lower than the other portion when the member is horizontal, a resilient bar rigidly connected with the curtain rod engaging member and extending downward therefrom, the said bar being adapted for engaging an edge portion of the curtain to press it against the wall and thus hold it against movement relatively to the bar, and clamping means carried by the curtain rod engaging member and engageable with the bottom of the rod to hold the said member in fixed relation to the rod, the last said means tending to tilt the member downward about the rod engaging portion nearer the wall and thereby tending to swing the downward extending bar toward the wall to more firmly engage the curtain.

3. A device for use in conjunction with a curtain, a horizontal supporting rod therefor and 50

2,554,106
6

a vertical wall adjacent one end of the rod, the said device comprising in combination a generally vertical bar adapted to be positioned closely adjacent the wall for releasably engaging an edge portion of the curtain to press it against the wall and thus hold it against movement relatively to the bar, the said bar having its top portion bent to form two integral curtain rod receiving loops spaced longitudinally of the rod with the loop nearer the wall lower than the other, and means connected with the said loops and adapted to engage the bottom of the rod to prevent longitudinal movement along the rod and to tilt the bar about the lower loop so as to swing the lower end of the bar toward the wall.

4. A device for use in conjunction with a curtain and a horizontal supporting rod therefor, the said device comprising in combination a generally vertical bar serving to engage an edge portion of the curtain to hold it against movement relatively to the bar, the said bar having its top portion bent to form two integral curtain rod receiving loops spaced longitudinally of the rod with a longitudinal connecting portion 25 between the loops and with a second longitudinal portion extending from the second loop toward the first loop, an element connected with the two said longitudinal portions and provided with a substantially vertical threaded aperture, a manually operable vertical screw extending through the threaded aperture in the said element, and a shoe at the top of the screw engageable with the bottom of the rod and serving when the screw is turned to clamp at least one 30 of the loops in firm engagement with the rod to prevent longitudinal movement therealong.
